UNITED STATES PATENT OFFICE.

GRIDLEY ADAMS, OF CHICAGO, ILLINOIS.

ENVELOP.

1,201,419.

Specification of Letters Patent.

Patented Oct. 17, 1916.

Application filed August 11, 1915. Serial No. 44,866.

To all whom it may concern:

Be it known that I, GRIDLEY ADAMS, a citizen of the United States, residing at Chicago, in the county of Cook and State 5 of Illinois, have invented new and useful Improvements in Envelops, of which the following is a specification, reference being had to the accompanying drawings, forming a part thereof.

10 The purpose of this invention is to provide an improved form of envelop, particularly designed and adapted to be returned to the original sender.

15 It consists in the elements and features of construction shown and described, as indicated in the claims.

In the drawings: Figure 1 is a plan view of the blank from which the envelop in question is formed. Fig. 2 is a perspective view 20 of the envelop as completed ready for use and before sealing. Fig. 3 is an elevation of the address side of the envelop when closed and sealed. Fig. 4 is a section at the line, 4—4, on Fig. 3. Fig. 5 is an elevation of the 25 envelop after having been sealed and opened.

The envelop which constitutes this invention is designed to have closed ends and one longitudinal edge open and adapted to be sealed, and when constructed so as to serve 30 all the purposes for which it is designed, has a flap extending from each of the sides, (front and back) at the edge which is open and adapted to be sealed. In carrying out these purposes the blank, A, comprises the 35 body area, forming the two sides, 1 and 2, of the envelop, and projecting from the end portion of one of said parts, as for example, the part, 1, two narrow flaps, 3 and 4, perforated at the lines forming the ends of the 40 body or folding line of the flap, and gummed upon the back or outer surface for adhering to the inner surface of the opposite side, 2, of the body for closing the envelop at the ends. From the two opposite longitudinal 45 edges of the front and back, 1 and 2, portions, 5 and 6, extend which are to form flaps extending from the open edge of the envelop when it has been folded to close the ends. One of these flaps, 5, has printed upon 50 its inner surface the address to which the envelop is to be returned, and upon the opposite surface it may have any form of communication, as, for example, instructions as to the manner of use of the envelop or any 55 other communication to be responded to or acted upon by the person to whom the en-

velop is sent out and by whom it is to be returned to the person whose address is printed upon said inner surface of said flap, 5. The said flap, 5, is gummed around 60 its margin on the outer surface so that it may be folded down upon the outer surface of the body of the envelop and gummed thereto concealing the communication printed upon the outer surface of the flap 65 and expose the address printed upon the inner (which then becomes the outer) surface of that flap, 5. The paper is preferably perforated along the line of folding, 6^a, of the flap, 6, at the open edge of the envelop. 70 Said flap, 6, is designed to be tucked into the envelop and the envelop is to be closed and sealed by the adhesion of the outer surface of the flap to the inner surface of the opposite side of the envelop body, and for that 75 purpose either the flap, 6, is gummed upon its outer surface along the fold and perforated line, as indicated at 10; or the inner surface of the opposite side, 1, is gummed as shown at 10^a, and both of these areas may 80 be gummed without objection and with the advantage of adapting the envelop to be sealed with both flaps, 5 and 6, turned in or with only the flap, 6, turned in, or with the flap, 6, detached and the flap, 5, turned out 85 or with both flaps detached. This flap, 6, may be wide enough to contain a considerable communication which may be in response to or in compliance with the suggestions of the communication which may 90 be printed upon the outer side of the flap, 5, and concealed when the flap is folded down to expose the address as above described. Such communication is indicated at 11 on the outer surface of the flap, 6, by the opening address and lines ruled for writing, and 95 on the opposite surface of the flap by the ruled lines and conclusion for signature.

The modes of use of such an envelop are various. By tucking in both of the flaps, 100 5 and 6, it becomes an unsealed letter to a person whose address may be placed on the space on the side, 1, which will be covered by the flap, 5, when it is folded out and gummed down as described, said flap then 105 covering also the stamp applied in the upper right-hand corner marked "Stamp." This envelop is particularly intended, among other things, to be used for sending out to parties from whom responses are desired by 110 the original sender, for the sake of which he is willing and desirous of paying the postage

upon the return of the envelop to him, and for which purpose instructions with regard to such return without postage are desirably printed upon the outer surface of the flap, 5, so as to be completely concealed when that flap is gummed down exposing the address on the other side. When thus used, the other flap, 6, is designed to contain a communication which the original sender desired to receive from the person to whom the envelop 10 was sent out. The envelop is also particularly designed to be preserved in connection with the communication which may be contained upon its flap, so that when filed it 15 shall constitute a complete record, not only of the correspondence which passed between the parties, but also of the place and dates of mailing and receiving as indicated by the post-marks which the envelop will receive in 20 passing through mail. For this purpose the end flaps, 3 and 4, are perforated as described at the folding line and the folding line at the flap, 6, is perforated, the intention being that when the envelop is received, it 25 shall be opened by rupture at all three of said perforated lines, so that lying flat the communication on the flap, 6, will be exposed and may be read upon both sides by turning up the free edge of the flap to read the side 30 which will be facing down or toward the body member, 1, of the envelop. I do not limit myself, however, to the particular manner of use of the envelop, but claim its construction as described, adapting it for use 35 in any of the ways above indicated. To facilitate opening as described, the gum securing the narrow flaps, 3 and 4, stops a little short of the folding line, 6^a, so that a cutter can be introduced easily to sever the 40 flap, 6, at that line.

I claim:—

1. An envelop open at one edge and having one side extended from said edge to form a foldable flap dimensioned to approximately cover said side of the envelop when folded thereover and gummed on that surface which is continuous with the outer face of said envelop side to permit sealing the flap over said face of the envelop.
2. An envelop open at one edge and having one side extended from said edge to form a foldable flap dimensioned for tucking into

the envelop through said open edge, adhesive being applied on one of the two surfaces which face each other along the margin of the opening when said flap is so disposed within the envelop, said adhesive covering only an area closely adjacent said margin to avoid sealing down the entire area of the flap. 55

3. An envelop open at one edge and having both sides extended from said edge to form foldable flaps, one of said flaps being dimensioned to approximately cover one side of the envelop and having adhesive applied to that surface which is continuous with the outer face of the envelop side from which the flap extends to permit sealing said flap over such outer face of the envelop, the other flap being dimensioned for tucking into the envelop through said open edge, and adhesive being applied on one of the two surfaces which face each other along the margin of the opening when said last-mentioned flap is tucked into the envelop, said adhesive covering only an area closely adjacent said margin to avoid sealing down the entire area of said flap. 70 75

4. An envelop having at two opposite edges folded flaps gummed onto one side of the body for closing the envelop at said two edges, the envelop being open at one edge and having one side extended from said open edge to form a flap foldable at the line of said edge and dimensioned for tucking into the envelop through said open edge, an adhesive area being provided at one of the surfaces which face each other along the margin of the opening when said flap is so tucked in, the adhesive covering only an area closely adjacent said margin to avoid sealing down the entire area of the flap, and all three flaps being perforated at their folded lines to permit opening the envelop at three edges, and unfolding it to flat form to give access to the unsealed area of the flap which was tucked in as described. 90 95

In testimony whereof I have hereunto set my hand at Chicago, Illinois, this 12th day of July, 1915.

GRIDLEY ADAMS.
